UNITED STATES PATENT OFFICE

2,492,099

RETRACTING TYPE THEATER CHAIR

John J. Kenny, Grand Rapids, Mich., assignor to
 American Seating Company, Grand Rapids,
 Mich., a corporation of New Jersey

Application December 5, 1947, Serial No. 789,926

2 Claims. (Cl. 155—116)

1

The present invention relates to chairs, and more particularly to chairs of the retracting type for use in theaters, auditoriums and the like.

The primary objects of the invention are to provide an improved chair of the retracting type wherein the chair occupant may move the seat rearwardly to permit others to pass in front of him without his having to rise from the seat; to provide such a chair in which the chair seat and back are mounted on spaced upright standards for forward and rearward movements, the mounting mechanism being comprised solely of links and without any rollers or the like; to provide such a chair in which the seat may be upwardly turned in either the forward or retracted position of the chair; and in general to provide such a retracting chair which is simple and reasonably economical in manufacture, smooth and efficient in operation and attractive in appearance.

An illustrative embodiment of the invention is shown in the accompanying drawing, wherein:

Figure 1 is a right hand side elevational view of a retracting chair in its forward position of occupancy, the chair seat and back being mounted at their opposite sides on spaced upright chair supporting standards by means of like right and left link mechanism;

Figure 2 is a view similar to Figure 1 and showing the chair in its retracted position of occupancy; and

Figure 3 is a fragmentary front elevational view of the left hand side portion of the chair, certain parts thereof being shown in vertical section taken on line 3—3 of Figure 2.

Referring now in detail to these drawings wherein like parts are designated by the same numerals in the several views, the retracting chair there shown is mounted on spaced, upright chair-supporting standards 10 each of which is provided with a conventional arm rest 11 at the top thereof. The chair comprises a seat 12 having a sheet metal foundation or "pan" 13 and a conventional upholstered seat cushion 14, and a back 15 having an upholstered cushion 16 mounted on a sheet metal back plate 17 having forwardly extending side flanges or wings 18.

Front supporting links 19 have their lower ends pivotally connected to the lower forward portions of the standards 10 respectively, and rear supporting links 20 have their upper ends pivotally connected to the upper rearward portions of the standards 10 respectively. Carriers 21 at opposite sides of the chair have their forward ends pivotally connected to the upper ends of the front links 19 respectively and have their rearward ends

2

pivotedly connected to the lower ends of the rear links 20 respectively. The carriers 21 are thus mounted adjacent the standards for forward and rearward movements.

5 The seat 12 is mounted on the carriers 21 for forward and rearward movements therewith by means of seat mounting brackets 22 having outwardly turned flanges 23 secured as by means of machine screws 24 to inwardly turned flanges 25 on the carriers 21. The pan 13 of the seat 12 has its opposite sides rotatably mounted on inwardly extending spindles 26 on the seat mounting brackets 22, and the seat is thus turnable about a horizontal axis to a lowered position for occupancy or to a raised position (not shown) to facilitate sweeping under the chair.

10 The chair back 15 is pivotally connected at its bottom to the carriers 21 by means of the same pins or rivets 27 which connect the lower ends of the rear links 20 to the rearward ends of the carriers, and which rivets pass through apertures in the wings 18 of the back plate 17. The back is supported above its pivotal connections to the carriers by means of back-actuating levers 28 which have their lower forward ends pivotally connected to the front links 19 and have their upper rearward ends pivotally connected to the wings 18 of the back plate 17. It will be seen that, as the chair is retracted from its forward position shown in Figure 1 to its retracted position shown in Figure 2, the back-actuating levers 28 turn the back from an upwardly-rearwardly inclined position to a near-vertical position, so that the space to the rear of the chair utilized for retraction is kept to a minimum. When the chair is returned to its normal forward position of occupancy, the back-actuating levers 28 cause the back to assume again its upward-rearward inclination for the greater comfort of the occupant.

15 Stop means are provided for limiting the forward and rearward movements of the chair. As here shown these means comprise front stops 29 which are contacted by the front links 19 to limit forward movement of the chair, and rear stops 30 which are contacted by the rear links 20 to limit rearward movement of the chair. These stops 29 and 30 are here shown integrally cast with the standards 10, but they may be separate elements and may be made of rubber to cushion and silence the stopping of the chair.

20 It will thus be seen that the invention provides a chair of the retracting type which is extremely simple and economical in construction, and which is smooth and quiet in operation, and while but one specific embodiment of the invention has

been herein shown and described it will be understood that numerous details may be altered or omitted without departing from the spirit of the invention as the same is defined by the following claims:

I claim:

1. In a chair, spaced upright chair-supporting standards, front links having their lower ends pivotally connected to the lower forward portions of said standards, rear links having their upper ends pivotally connected to the upper rearward portions of said standards, carriers having their forward ends pivotally connected to the upper ends of the front links and having their rearward ends pivotally connected to the lower ends of the rear links, a chair seat mounted on the carriers, a chair back having its lower opposite sides pivotally connected to the rearward ends of the carriers, a back-actuating link having its lower forward end pivotally connected to a front link and having its upper rearward end pivotally connected to the chair back above the latter's pivotal connections to the carriers, and stop means for limiting the forward and rearward movements of the carriers.

2. In a chair, spaced upright chair-supporting standards, front links having their lower ends

pivotally connected to the lower forward portions of said standards, rear links having their upper ends pivotally connected to the upper rearward portions of said standards, carriers having their forward ends pivotally connected to the upper ends of the front links and having their rearward ends pivotally connected to the lower ends of the rear links, a chair seat mounted on the carriers, a chair back having its lower opposite sides pivotally connected to the rearward ends of the carriers, back-actuating links having their lower forward ends pivotally connected to the front links and having their upper rearward ends pivotally connected to opposite sides of the chair back above the latter's pivotal connections to the carriers, and stop means for limiting the forward and rearward movements of the carriers.

JOHN J. KENNY.
